[57] CLAIM

The ornamental design for a flywheel for a clutch, especially for automotive racing applications, as shown and described.

DESCRIPTION

FIG. 1 is a front elevational view illustrating a flywheel for a clutch, especially for automotive racing applications in accordance with my new design; and,

FIG. 2 is a left side elevational view of the flywheel for a clutch, especially for automotive racing applications as illustrated in FIG. 1.

The rear elevational view of the flywheel does not form part of the claimed design and the side of the flywheel has a continuous design along its periphery.

The interior circumferential side of the flywheel does not form part of the claimed design.
